UNITED STATES PATENT OFFICE.

EDWARD HERSKOVITZ, OF CHICAGO, ILLINOIS, ASSIGNOR TO PEERLESS LIGHT COMPANY, OF CHICAGO, ILLINOIS.

DESIGN FOR A LAMP BASE.

Application filed June 25, 1925. Serial No. 13,886. Term of patent 3½ years.

To all whom it may concern:

Be it known that I, EDWARD HERSKOVITZ, residing at Chicago, in the county of Cook and State of Illinois, have invented a new, original, and ornamental Design for Lamp Bases, of which the following is a specification, reference being had to the accompanying drawing, forming part thereof,

I claim:

The ornamental design for a lamp base, as shown.

EDW. HERSKOVITZ.
